(57) **CLAIM**

The ornamental design for a pedicure device as shown and described.

DESCRIPTION

FIG. 1 is a front perspective view of a pedicure device of the present invention showing our new design;

FIG. 2 is another perspective view thereof;

FIG. 3 is a front elevational view thereof;

FIG. 4 is a rear elevational view thereof;

FIG. 5 is a side elevational view thereof;

FIG. 6 is an opposing side elevational view thereof;

FIG. 7 is a top view thereof; and,

FIG. 8 is a bottom view thereof.

The dash-dash broken lines shown herein illustrate portions of the device that form no part of the claimed design. The dash-dot-dash broken lines illustrate a boundary of the claimed design and form no part thereof.

1 Claim, 5 Drawing Sheets
